ABSTRACT OF THE DISCLOSURE

Tube-rolling mill comprising a central mandrel, two axially spaced housings encircling said mandrel, a plurality of rolls positioned between the housings with one end pivotally mounted in each housing, and means for turning one housing about the mandrel so as to alter the angle between the axes of the rolls and that of the mandrel and produce a greater thickness of tube wall as the trailing end of the tube approaches the mandrel. A tube wall having a thickness less than $\frac{1}{11}$ of the outer diameter of the tube throughout most of its length is produced.

This invention relates to a new rolling mill which can be used for the manufacture of metal tubes, particularly steel tubes.

It is known that for the purpose of producing a tube of this type the starting material is generally a billet which is pierced at its centre to form a blank, into which a mandrel is introduced, and which is engaged between the rolls of the rolling mill, which are usually three in number and which give rise to a forced reduction of the thickness of the tubular blank.

The rolls are bodies of revolution which are driven rotationally by a suitable device and which, viewed in the direction of rolling, have in succession a conical portion effecting the engagement of the blank, and then a portion having a fairly abrupt increase in diameter which effects the actual rolling, and finally a substantially cylindrical portion which effects the smoothing of the outer surface of the tube.

It is also known that rolling mills comprising three rolls of this type do not make it possible to produce industrially tubes having a slight thickness in relation to their diameter.

For example, with mills of this type it is generally possible to produce only tubes in which the ratio of the outer diameter to the thickness of the tube is between 4 and 11.5.

In practice, it is found that when it is desired to obtain smaller tube thicknesses, the difficulties arise in the rolling of the terminal portion of the blank because the great reduction of thickness produced by the rolling gives the tube section (which, since it is its end which is involved, can be held only by a rigid portion situated upstream of the rolls) a trilobate shape which very rapidly leads to the jamming of the blank or to its tearing, and frequently damages the rolling mill.

The method according to the invention ensures that the rolling mill automatically presents a different adjustment depending on whether it is working on the body of the hollow blank which it is rolling and the thickness of which it is considerably reducing, or whether it is working on the end of the blank, in which case it gives rise only to a smaller reduction of the thickness of the blank, while imparting to the latter only a reduced speed of advance.

The present invention has an object a new method of rolling thin tubes, said method being essentially charac-

2

terised by the fact that the tubular blank is rolled in a rolling mill in order to give it the required thickness over the greater part of its length, whereupon the reduction of thickness of the tube obtained by rolling is reduced near the end of the blank.

In one particular embodiment of the invention for the rolling of steel tubes, a short portion, for which the ratio of the diameter to the thickness of the tube is lower than about 11, is left at the end of the blank.

In a preferred embodiment a reduction of the spacing of the rolls is also effected during the rolling of the end of the tube.

The present invention has as object the new industrial product constituted by a rolling mill for thin tubes, which is essentially characterised by the fact that each roll is mounted by two bearings comprising swivel-joints or similar devices, on the one hand on a plate which is fixed in relation to the frame of the rolling mill and on the other hand on a movable plate the angular position of which in relation to the fixed plate can be varied with the aid of any means, in order to bring to a smaller value the reduction of thickness during the rolling of the end of the tube.

In a preferred embodiment of the invention, each swivel-joint bearing supporting a roll is mounted by its plate in such a manner as to be able to move radially in relation to the latter, each roll being held in the working position by means of counter-pressure acting on a piston solid to the bearing, in such a manner that the roll cylinders can move automatically apart from one another when they are subjected to abnormal stresses.

The present invention likewise has as object a particular form of execution of the method indicated hereinabove, with is characterised by the fact that the reduction of thickness of the tube at the end of the latter is limited by pivoting the two plates of the rolling mill which has just been described in relation to one another.

Finally, the present invention has as object thin tubes rolled by the above-described method, said tubes being particularly characterised by the fact that they have a zone of greater thickness at one of their ends.

One particular embodiment of the invention will now be described, which will illustrate in greater detail the different characteristics of the invention.

The description of this embodiment, which is given solely by way of illustration and without limitation in any way, refers to the accompanying drawings, in which:

FIGURE 1 is a diagrammatical view in perspective showing how in accordance with the invention the distances separating the rolls of the rolling mill can be varied,

FIGURE 2 illustrates diagrammatically in section a rolled tube according to the invention,

FIGURES 3 and 4 illustrate diagrammatically the positions of the rolls of the rolling mill which correspond to the sections III—III and IV—IV in FIGURE 2,

FIGURE 5 is a front view, partly cut away, of a form of construction of a rolling mill according to the invention, and

FIGURE 6 is a view in section on the line VI—VI in FIGURE 5.

In FIGURE 1, a roll 1 is diagrammatically illustrated which turns on two swivel-joint bearings 2 and 3, which are situated respectively on a fixed plate 4 and a movable plate 5.

Two other rolls (not illustrated) are mounted in the same manner on swivel-joint bearings 2', 2'' and 3', 3''.

According to the invention, the movable plate 5 is mounted to be pivotable about axis 6 which corresponds to the rolling axis of the hollow blank.

The movable plate 5 is provided with two movable

stops 7 and 8 which limit its pivoting movement by bearing against the fixed stops 9 and 10, which may be adjustable.

The hydraulic or pneumatic device 11 has been shown diagrammatically, which enables the plate 5 to be rotated in relation to the plate 4.

It is clear that when the angular position of the plate 5 in relation to the plate 4 is varied, the distance between the roll 1 and the axis 6 is likewise varied. In fact, any pivoting of the plate 5 in relation to the plate 4 has the effect of varying the warping of the quadrilateral constituted by the axis 6, the line 2-3, and the radii of the plates 4 and 5 which pass respectively through the bearings 2 and 3 and through the axis 6.

Since through its construction the roll 1 is situated substantially in the centre of the segment 2-3 it is obvious that any increase in the warping of the quadrilateral previously defined has two effects, namely of firstly reducing the distances between the roll 1 and the axis 6 and secondly increasing the inclination of the axis of the roll 1 in relation to the axis 6 and consequently of increasing the rolling pitch, that is to say the speed at which the blank is driven by the rolls.

It is likewise evident that any reduction of the warping of the quadrilateral in question will produce the reverse effects.

It will therefore be understood in these circumstances that if, after the position of the plate 5 has been adjusted (by adjusting the position of the fixed stop 9), so as to obtain a sufficiently intensive rolling effect to make the tube wall as thin as is desired, it is sufficient, when the end of the rolling of the blank is reached, to utilise the device 11 to pivot the plate 5, which assumes the position illustrated in FIGURE 1, in order to move the rolls away from the axis 6 and leave a greater thickness on the terminal portion of the blank. The disadvantages which were mentioned hereinabove and which were inherent in previously known rolling mills are thus avoided.

In section in FIGURE 2 a tube rolled in the manner just described is illustrated, the greater part of the tube having a diameter D_1 which corresponds to a relatively slight wall thickness in relation to the diameter of the tube.

At the end of the rolling (towards the left-hand end of the tube) the movable plate has been pivoted in the direction of the arrows F (FIGURE 3) in order to bring it from the position occupied in FIGURE 3 to the position occupied in FIGURE 4, thus making it possible to reduce the rolling effect and give the blank a diameter D_2 greater than D_1 . In FIGURES 5 and 6 the fixed plate 4, in relation to which the movable plate 5 is adapted to pivot by means of suitable bearings, is found once again.

These figures also illustrate the pairs of swivel-joint bearings 2-3, 2'-3', and 2''-3'', in which the shafts 12, 12', and 12'' supporting the rolls 1, 1', and 1'' are mounted.

These shafts 12, 12', 12'' are in turn driven rotationally by corresponding drive shafts 13, 13', and 13'', to which they are connected through cardan points.

It can be seen in FIGURE 5 how the bearing blocks 14, 14', and 14'' can slide radially in relation to the fixed plate 4. The same is true of the bearing blocks situated on the movable plate 5.

As can be seen clearly in FIGURE 6, the bottom portion 15 of each bearing block constitutes a cylinder inside which a piston 16 is movable, so that by delivering a fluid under pressure to the chamber 17 thus formed it is possible to hold the rolls in their working position (the bottom of the piston 16 striking against a corresponding shoulder on the cylinder 15) while permitting the rolls to yield in the event of their being subjected to excessive stressing, which would correspond in the chamber 17 to a pressure higher than the pressure to which the fluid in question is adjusted.

This device can be operated for example by utilising an adjusted valve which allows the fluid to escape to the outside when the pressure exceeds a given value in the chamber 17.

5 The position of the rolls is adjusted by effecting the axial displacement of the piston 16 of each of the bearings with the aid of a wheel 18 driven rotatably by a worm 19 and keyed on the threaded body of the piston 16 which engages in a fixed nut 20.

10 As can be seen in FIGURE 5, all the worms 19 controlling the displacement of bearings on the same plate are made solid to one another by bevel gears 21 and 22, so that the bearings 3, 3', 3'' or 2, 2', 2'' are always acted on simultaneously so as to cause them to move the same distances in relation to the axis 6 of the blank 23.

In FIGURE 6 it can be seen how the blank contains in its centre a mandrel 24 against which the rolling is effected.

20 FIGURE 5 shows how the pivoting of the movable plate 5 is effected with the aid of the cylinder 25 which is articulated at 26 on the body of the rolling mill and in which the piston 27 is movable, the rod of said piston being articulated at 28 at a point on the movable plate 5.

The pivoting is effected by delivering a fluid under pressure on one or the other side of the piston 27.

25 In the embodiment illustrated in FIGURES 5 and 6, the movable stop 7 bears against a fixed stop 9 which is adjustable through the fact that it is mounted by a threaded body 9' in a nut 9'' solid to the frame of the rolling mill. A lock-nut 29 enable the fixed stop 9 to be locked in the desired position.

30 In the embodiment illustrated in FIGURES 5 and 6, the other movable stop 8 bears against a fixed stop 10 which in turn is supported against the rod 10' of the piston 10'' which moves in the cylinder 30.

35 A device of this type enables the stop 10 to be initially placed in the position which corresponds to the position in which the piston 10'' is pushed upwards, and then progressively to vary the position of the stop 10, for example by delivering through a calibrated aperture the fluid contained in the bottom portion of the cylinder 30, while a fluid under pressure is introduced into the top portion of said same cylinder 30 so as to move the piston 10'' progressively downwards.

40 45 It will be understood that through this feature of the invention, or with the aid of any suitable means enabling the movement of the stop 10 to be adjusted in dependence on time or on the length of the tube rolled, it is possible to vary correspondingly the thickness of the tube rolled in this manner.

50 This feature makes it possible in particular to roll tubes of relatively slight thickness in relation to their diameter, the rolling thickness being abruptly brought to a normal value on the rear portion of the blank. The pivoting of the movable plate may for example be effected automatically in this case with the aid of a photoelectric cell which detects the passage of the rear end of the blank.

55 By effecting suitable displacements of the stops this feature of the invention enables the tube to be given 60 desired additional thicknesses at certain points or even to produce tubes having a thickness which is continuously variable over a considerable length.

65 65 By means of this characteristic it is possible in particular to avoid forging, which in conventional processes is often necessary in order to be able to provide screw threads for the purpose of making joints at the end of a length of tube.

70 As can be seen in FIGURE 5, the bearing blocks 14, 14', and 14'' are each likewise made solid to two pistons 31 which move under the action of a compressed fluid.

75 This device in particular makes it possible to bring the rolls abruptly backwards as soon as the pressure ceases to prevail in the chamber 17.

It is clearly understood that the embodiment described hereinabove as an example is not intended as a limitation

and that it may undergo all desirable modifications without thereby departing from the scope of the invention.

What I claim is:

1. Method of rolling a thin metallic tube from a pierced billet by means of a rolling mill equipped with a plurality of rolls which cooperate with a central mandrel for carrying the pierced billet, and with means for varying the angular position of said rolls with respect to the axis of said mandrel and for varying the thickness of the tube being produced, said method comprising the steps of rolling the pierced billet to a wall thickness less than $1/11$ of the outer diameter of said billet for the greater part of its length and then changing the setting of said rolls to reduce the angle between the axes of said rolls and that of said mandrel and produce a greater wall thickness as the trailing edge of said billet passes through said mill.

2. Method as claimed in claim 1 in which the thickness of the trailing portion of said billet wall is kept greater than $1/11$ of the outer diameter of the billet.

3. Tube rolling mill comprising a central mandrel positioned to be encircled by a tube being advanced axially therealong, a pair of housings axially spaced along said mandrel and a plurality of rolls positioned around said mandrel between said housings, each roll being pivotally and rotatably mounted at one end in one of said housings and at the other end in the other of said housings, at least one of said housings being mounted to turn about said mandrel and thereby alter the angular position of the axes of said rolls relative to that of said mandrel.

4. Tube rolling mill as claimed in claim 3 comprising means for automatically turning said last mentioned housing when the trailing end of a tube being rolled approaches said rolls.

5. Tube rolling mill as claimed in claim 3 comprising three rolls symmetrically distributed about said mandrel.

6. Tube rolling mill as claimed in claim 3 in which said roll ends are mounted in bearings which are supported in said housing for radial movement relative to the axis of said mandrel.

7. Tube rolling mill as claimed in claim 3 in which said roll ends are mounted in bearings supported in said housings by fluid pressure actuated means which are movable radially of said mandrel.

8. Tube rolling mill as claimed in claim 3 in which the means for turning the movable housing comprises a photo electric cell positioned to be controlled by the passage of said pierced billet beyond a predetermined point as it travels through the machine.
